United States Patent Office

Des. 211,548
Patented June 25, 1968

211,548

DISPLAY CASE

Thomas H. Hayes, Roanoke, Va., assignor to Creative Packaging Incorporated

Filed Mar. 6, 1967, Ser. No. 6,067

Term of patent 14 years

(Cl. D80—11)

FIG. 1 is a front perspective view taken from one side of a display case showing my new design;

FIG. 2 is a rear elevational view thereof;

FIG. 3 is a bottom plan view thereof; and

FIG. 4 is an elevational view taken from the side opposite that shown in FIG. 1.

I claim:

The ornamental design for a display case, as shown.
